UNITED STATES PATENT OFFICE.

HENRY HORAN, OF EAST ORANGE, NEW JERSEY, ASSIGNOR TO HARTFORD CARPET COMPANY, OF HARTFORD, CONNECTICUT.

DESIGN FOR CARPET.

SPECIFICATION forming part of Design No. 11,831, dated June 29, 1880.

Application filed February 12, 1880. Term of patent 3½ years.

To all whom it may concern:

Be it known that I, HENRY HORAN, of East Orange, in the county of Essex and State of New Jersey, have invented a new and original 5 Design for a Carpet, of which the following is a specification.

This invention relates to a new and original design for carpets, oil-cloths, and similar fabrics.

10 It consists in the novel grouping and configuration of figures, hereinafter more fully described.

The accompanying photograph illustrates a face view of a carpet having my new design.

15 The design is composed of floral groups A, B, C, D, E, and F on a background, G. The more prominent, A, is composed of leaves, branches, roses, and rose-buds. Group B is composed of a graceful spray of leaves and 20 star-flowers and rose-buds. Group C is composed of a bunch of leaves and flowers and buds. Group D is composed of large leaves and of a few flowers. Group E is a spray of

leafy branches, flowers, and leaves; and group F is composed of branches of rose-leaves and 25 moss-rose buds. The leaves, branches, flowers, and buds of the several outside groups extend over the ground G toward the central group, A, which is surrounded by the other groups.

30 I claim—

1. The design for a carpet, consisting of the groups A B C, substantially as shown.
2. The design for a carpet, consisting of the groups A B D, substantially as shown.
3. The design for a carpet, consisting of the groups A C E, substantially as shown.
4. The design for a carpet, consisting of the groups A B F, substantially as shown.
5. The design for a carpet, consisting of the 40 group A and surrounding groups B C D E F, substantially as shown.

HENRY HORAN.
